(No Model.)

M. M. CLARK.

BOW FACING OAR.

No. 325,055.

Patented Aug. 25, 1885.

UNITED STATES PATENT OFFICE.

MARCUS M. CLARK, OF VERMONT, ILLINOIS.

BOW-FACING OAR.

SPECIFICATION forming part of Letters Patent No. 325,055, dated August 25, 1885.

Application filed June 9, 1885. (No model.)

To all whom it may concern:

Be it known that I, MARCUS M. CLARK, of Vermont, in the county of Fulton and State of Illinois, have invented a new and Improved 5 Bow-Facing Oar, of which the following is a full, clear, and exact description.

The object of my invention is to provide a new and improved oar, which is so constructed that the person propelling the boat by means 10 of the oar can face the bow.

The invention consists in the combination, with an oar and a lever, of a plate or rod, forming a curved guide for the fulcrum of the lever, and of crossed rods connecting the lever and 15 oar at opposite sides of the fulcrum.

Reference is to be had to the accompanying drawings, forming a part of this specification, in which similar letters of reference indicate corresponding parts in all the figures.

20 Figure 1 is a plan view of my improved bow-facing oar, part of the boat on which it is held being shown. Fig. 2 is a side view of the mechanism, and longitudinal sectional view of the boat. Fig. 3 is a cross-sectional view. 25 Fig. 4 shows a modification in side view.

The oar A is pivoted near its inner end to a plate, B, and has its inner end connected by a rod, C, with the outer end of a lever, D, provided with a pivot, E, which works in a curved 30 slot, F, in the plate B, near the front end of the same. The oar is connected outside of its pivot by a curved rod, H, with a point on the lever D some distance inward from the pivot—that is, between the handle end and the pivot. The rods C and H cross, as shown in Figs. 1 and 2.

The ends B' of the plate B are bent down at right angles, and provided with pivots I, which work in sleeves J on the upper ends 40 of pivots K in sockets M on the inside of the boat L.

The oar and its operating devices can easily be removed from the boat by lifting the pivots K out of the sockets M, and the oar can 45 easily be swung down into the boat below the gunwale.

The plate B can turn on its end pivots in the sleeve J, thus permitting of lifting the oars out of the water.

50 The lever D has a movable fulcrum, which can be moved in the slot F close to the inner edge of the plate B, thus permitting of swinging the oar inside of the boat.

By pulling the inner or handle ends of the levers D toward the stern the outer ends of 55 the oars are moved in the like direction, and by moving the inner or handle ends of the levers D toward the bow the outer ends of the oars are moved in the same direction.

The plate B may be replaced by a rod, O, 60 having its ends bent down rectangularly to be passed into the sockets M, and the front part of the said rod is curved the same as the slot F.

On the rear end of the rod a piece, P, is mounted to rock, which has a pivot, P', which 65 is passed through the oar; and on the curved end of the rod a piece, R, is mounted to rock and slide, and is provided with a pivot, R', for the lever D.

The connections or pivots of the rods C H 70 on the oar and lever D are equidistant from the fulcrums.

In both constructions the oars can easily be dipped and raised, can be swung into the boat, and the entire device can easily be detached. 75

Having thus described my invention, I claim as new and desire to secure by Letters Patent—

1. The combination, with an oar and a hand-lever, of a rod or bar on which they are pivoted at the side of the boat, and of cross-rods 80 connecting the oar and lever at different sides of the fulcrums of said oar and lever, one end of each rod being secured to the oar, and the other end of each rod being secured to the lever, substantially as herein shown and de- 85 scribed.

2. The combination, with an oar and a lever, of a bar or plate forming a curved guide for the fulcrum of the lever, and of crossed rods connecting the oar and lever at opposite 90 sides of the fulcrums, substantially as herein shown and described.

3. The combination, with an oar and a lever, of a plate or rod on which they are mounted, crossed rods connecting the oar and lever 95 at opposite sides of their fulcrums, and of sockets on the boat open at their tops, for holding the plate or rod detachably to the boat, substantially as herein shown and described.

MARCUS M. CLARK.

Witnesses:

EDWARD DEOBLER,
BURR WITCHELL.
